(57) **CLAIM**

The ornamental design for a jewelry medallion, as shown and described.

DESCRIPTION

FIG. 1 is an isometric view of a jewelry medallion showing my new design.

FIG. 2 is a front elevation view thereof, with the rear elevation view being a mirror image thereof.

FIG. 3 is a right side elevation view thereof with the left side elevation view being a mirror image thereof.

FIG. 4 is a top plan view thereof; and,

FIG. 5 is a bottom plan view thereof.

The broken lines shown in the Figures depict environmental subject matter only and are not part of the claimed design.
